STRIP SHINGLE CONSTRUCTION

Reid G. Badeau, Wausau, Wis.

Application August 23, 1944, Serial No. 550,709

4 Claims. (Cl. 108—7)

This invention relates to strip shingle constructions, and is more particularly concerned with a strip shingle construction embodying uniformly spaced individual shingles of standard construction which are interconnected for facility in packing and shipping as well as facilitating the handling and laying thereof, while the shingles when laid retain the advantageous functions of standard shingles laid individually together with other advantages as will hereinafter appear.

The present invention is to be differentiated from prior integral strip shingle constructions such as disclosed in the patent to G. B. Ferguson Reissue 15,439, dated August 29, 1922, wherein the strip shingle is in fact a single elongated strip of roof covering material having cut-out portions at regularly spaced intervals extending in from one edge thereof for a distance equal to the weather exposed portion of the strip whereby to simulate individual shingles.

While upon superficial examination of the Ferguson structure, it would appear that individual standard shingles are employed on a backing strip, it is to be noted that the strip is of substantial thickness and corresponds to the body portion of the shingles themselves, and that the strip is coated with asphalt and crushed slate in the provision of the shingle portions proper.

Furthermore, in the Ferguson structure the spaces between adjacent shingle portions are substantially interrupted between the closed ends of the cut-outs and the opposed edge of the strip whereby the usual and desirable ventilating properties of individual shingles laid in spaced relation is seriously affected.

In addition, the usual base felt material for shingles of which the strip in Ferguson is constructed and capable of supporting the layer of asphalt and slate is from $\frac{1}{8}$ to $\frac{1}{16}$ inch thick, and accordingly could not be readily bent upon itself as the same would be subject to breaking upon folding to package form for storage and transportation of the strip shingles to points of use. Such a disadvantage is also overcome by my improved construction.

A primary object of the present invention is the provision of a strip of individual shingles flexibly hinged together whereby they may be readily folded in package form as required while at the same time retaining the distinctive and desirable ventilating properties of the common individual shingles when separately laid in uniform spaced relation.

A further object of the invention is the provision of a plurality of standard weight and sized

individual shingles interconnected in uniform slightly spaced relation by means of a single relatively thin and highly flexible strip of material attached to the faces of the shingle, and having one edge thereof disposed between and parallel with the ends of the shingles, said edge defining a guide for locating thereon at the weather ends thereof another series of interconnected shingles.

A still further object of the invention is the provision of an assembled strip shingle structure as an article of manufacture, including a plurality of shingle elements each of substantial thickness which are interconnected in spaced relation by a relatively wide strip of highly flexible material having one edge thereof aligned with the ends of the shingles to be concealed when laid, the strip being substantially thin and flexible throughout whereby one or more strips of shingles may be folded in package form without any liability of the connecting strip breaking or cracking across the strip.

A still further object of the invention is the provision of strip shingles embodying a plurality of individual shingles interconnected in slightly spaced relation by a thin strip of material having one edge thereof disposed intermediate the ends of the shingles and parallel therewith, and the other edge projecting materially beyond the ends of the shingles to be concealed, a distance substantially equal to the non-overlapped portions of the shingles of successive layers thereof, whereby such projections form in effect a continuous base material layer between the shingles and the roof boards, as well as a means for greatly enhancing the weatherproofing qualities and means for securing the shingles in desired relation on a roof.

A still further object of the invention is the provision of a strip shingle construction which is durable and which greatly expedites the transportation of and laying of the shingles.

Other objects and advantages will present themselves in the course of the following description, taken in connection with the accompanying drawing, wherein—

Figure 1 is a plan view of a section of strip shingles constructed in accordance with the present invention;

Fig. 2 is a fragmental plan view of several shingle strips in laid position;

Fig. 3 is an enlarged section in the plane of line 3—3 of Fig. 2;

Fig. 4 is an enlarged sectional view in the plane of line 4—4 of Fig. 2;

Fig. 5 is a view similar to Fig. 2 depicting a modified form of shingle; and

Fig. 6 is a section similar to Fig. 3 disclosing a modified construction.

Referring now in detail to the drawing by use of reference characters, 10 designates a section of a strip of assembled shingle elements constructed and connected in accordance with the present invention. The strips 10 may be of substantial lengths in the manufacture thereof and from which the required lengths for laying on any particular roof may be readily cut without the aid of special means.

The strip 10 includes a plurality of shingle elements 11 which are preferably of standard size and multiple layer construction on a felt base, and may have a surface layer of asphalt of any combination of materials of which shingles are usually constructed. The shingles 11 are hingedly interconnected by means of a substantially thin applied surface strip 12 which may be of any highly flexible yet strong sheet material.

The strip or web 12 is suitably adhered to the top, or outer, faces of the spaced shingles 11 and interconnects the shingles with their adjacent edges in the uniform spaced relation, and which uniform spacing not only enhances the appearances of the laid shingles but also provides for folding of a plurality of superposed strips in package form and provides desired ventilation in use.

The strip or web 12, as shown, is of substantial width and has one edge thereof alined with the ends of the shingles to be concealed when laid in courses, and the other edge which is parallel with the first edge disposed intermediate the ends of the shingles and providing an accurate and clearly visible guide for placement of the weather ends of the shingles 11 of another strip of shingles to be laid thereon. Preferably the strip 12 is somewhat wider than one-half the length of the shingle elements, and of course must be so if less than one-half the lengths of the shingles are to be exposed, as illustrated in Figs. 2 and 3.

It may be desirable, particularly for relatively flat roofs to project the strips 12 over the concealed ends of the shingles of a row of shingles in the form of extensions 12', as illustrated in Fig. 6. These extensions 12' should be of a length substantially equal to the distance between the upper ends of the successive rows of shingles whereby is provided a complete roof surface covering between the shingles and the roof boards or other surface, as illustrated in Fig. 6.

It is of course to be noted that the bends shown in Fig. 6 at the junction of the extensions 12' with the main body strips 12 are greatly exaggerated, and in the laying of standard relatively thin and flexible shingles the extensions would be substantially co-planar with the body strips 12.

It is to be particularly observed that the invention is not confined to square or rectangular shingle elements mounted and connected as herein disclosed as the same may be cut in the form of the shingles indicated in Fig. 5, whereby the effect of hexagonal shingles 11' is produced, etc. Other shapes, particularly as relates to the exposed portions of the shingles are clearly within the scope of the invention.

It is also to be observed that the spaces between adjacent shingles extend to the very bottom surfaces of the adjacent shingle elements and are not interrupted by any strip such as the strips 12, whereby the roof boards are capable of being positively ventilated to the same extent as if the shingles were individually laid upon the roof in

usual spaced relation. By the present invention, however, the spacing is absolutely uniform which could not be accomplished in individual laying of the shingles without the expenditure of considerable time and effort.

While the strips 12 desirably augment the insulating and waterproof capacity of the laid shingle strips, their most essential function is to interconnect the shingles from their upper or top surfaces in uniform spaced relation for expeditious folding into package form and must be strong enough for tightly stretching a strip of shingles on a roof with the lower ends of the shingles alined with the lower edge of a strip portion 12 of a previously laid strip of shingles, without noticeably spacing one layer from another.

Thus in the present improved construction the strip material 12 is in fact used as a carrying, bending and gauging medium only and is not a portion of the essential shingle body or its covering surface as in the Ferguson construction previously referred to.

The web or strips 12 may be of any desired highly flexible, strong but thin, material and may be of the same color as the shingles 11, or, if desired the strips may be of a different color, whereby a color effect would be produced particularly with the form of shingle indicated in Fig. 5 wherein relatively large portions of the strips are exposed. Relatively long strips 10 may be folded in package form somewhat as is proposed in the Ferguson patent, but it is found more desirable in packaging the strip of shingles to position two or three shingles intermediate adjacent folds, whereby the package would be of a length equal to the combined widths of two or three shingles in addition to the spaces therebetween.

While I have disclosed the invention in accordance with certain specific embodiments thereof, such are to be considered as illustrative only, and not restrictive, the scope of the invention being defined in the appended claims.

In some instances, it may be desirable to invert the strips of assembled shingle elements so that the carrier strips 12 thereof are disposed under the individual shingles 11. However, even when this is done, the lower edges of the carrier strips can still be used as straight edge guides for lining up the next succeeding strip shingle unit, since the carrier strip of the unit will be visible through the spaces between the individual shingles 11.

What I claim is:

1. A strip shingle construction comprising a plurality of shingles, a strip of substantially thin and highly flexible material adhered to the outer faces of the shingles and connecting same in strip form with their adjacent edges in uniform and slightly spaced relation, the strip extending to the ends of the shingles to be concealed and the width of the strip being equal to the width of lap between the shingles and those of an adjacent strip when laid on a roof and completely filling the space between the lapped portions of the shingles of the strips.

2. A strip shingle construction comprising a plurality of shingles, and a relatively thin flexible strip of material interconnecting the shingles with their edges in uniform spaced relation, a portion of the width of the strip being adhered to the outer faces of the shingles and having an edge thereof spaced a predetermined distance from the weather ends of the shingles, the re-

mainder of the strip being free and extending beyond the other ends of the shingles a distance substantially equal to the distance of said edge from the weather ends of the shingles.

3. A strip shingle construction comprising a plurality of shingles, and a relatively thin flexible strip of material adhered to the outer faces of the shingles and flexibly interconnecting the same with their adjacent side edges in uniform slightly spaced relation and their respective opposed end edges aligned, the strip being relatively wide and completely and uniformly covering the surface portions of the outer faces of the shingles to be lapped by the shingles of a succeeding strip thereof upon being laid, one edge of the flexible strip providing an unbroken and clearly visible guide line on the outer faces of the shingles for accurate positioning of the weather ends of said succeeding shingle strip when being laid thereon, whereby said strips

completely fill the space between overlapping shingle portions of successive rows of shingles.

4. A strip shingle construction comprising a plurality of shingles, and a relatively thin flexible strip of material interconnecting the shingles with their adjacent side edges in uniform spaced relation, a portion of the width of the strip being adhered to the outer faces of the shingles, and the remaining portion of the width of the strip being free and extending over and beyond the ends of the shingles to be concealed by the shingles of a succeeding strip thereof when being laid thereon, the width of said remaining portion of the strip being substantially equal to the distance between the upper ends of the shingles of successively laid strips thereof whereby providing for a continuous surface covering by the strips beneath the shingles.

REID G. BADEAU.
